UNITED STATES PATENT OFFICE

132,989

DESIGN FOR A KNITTING CONTAINER OR SIMILAR ARTICLE

Frances Fink, New York, N. Y.

Application December 27, 1941, Serial No. 104,878

Term of patent 3½ years

To all whom it may concern:

Be it known that I, Frances Fink, a citizen of the United States and a resident of the city, county, and State of New York, have invented a new, original, and ornamental Design for a Knitting Container or Similar Article, of which the following is a specification, reference being had to the accompanying drawing, forming a part thereof, in which Figure 1 is a perspective view of a knitting container showing my new design; and Fig. 2 is a side elevational view thereof.

I claim:

The ornamental design for a knitting container or similar article, as shown.

FRANCES FINK.
